HEAT EXCHANGE APPARATUS

Filed Sept. 20, 1951

UNITED STATES PATENT OFFICE

2,666,625

HEAT EXCHANGE APPARATUS

Wilbur M. Byerley, Crum Lynne, Pa., assignor to
Westinghouse Electric Corporation, East Pitts-
burgh, Pa., a corporation of Pennsylvania

Application September 20, 1951, Serial No. 247,512

4 Claims. (Cl. 257—32)

1

This invention relates to heat exchangers such as feedwater heaters employing hairpin tubes forming first and second passes, and more particularly, to a heater of the type provided with horizontal and enveloping baffles joined to outer and inner tube plates for isolating a portion of the first pass to form an integral drain cooler, the length of which is substantially less than that of the first pass.

In constructing a feedwater heater with which it is desired to provide integral drain cooler apparatus, there may be a decided thermal advantage in enclosing a section which includes all of the tubes in the first pass throughout a portion of the full pass length, to constitute the desired drain cooler apparatus. It has been proposed to achieve this advantage by utilizing sealing means or packing around each tube in the end baffle of the cooler section. In order to minimize leakage, however, it is desirable to expand the tubes into the baffle at the end of the cooler section, through the medium of a suitable, extended tube-expanding device. With this construction the baffle is required to move with the tubes as they expand and contract. It is, therefore, an object of the invention to provide an expansion joint structure having improved sealing characteristics suitable for use in the drain cooler section of such a feedwater heater.

It is another object of the invention to provide, in feedwater heater apparatus, an expansion joint between the enveloping baffle and tubes of an integral drain cooler section having tubes which are rolled solidly into a tube sheet and enclosed by the enveloping baffle, which expansion joint dispenses with flexible diaphragm means and is constructed and arranged to present favorable contour characteristics avoiding weak corner portions that might be subject to high stress concentrations.

A further object of the invention is to provide a differential expansion joint of the foregoing type comprising a plurality of overlapping and encircling strips of rust-resistant material wrapped around the baffle and tube plate portion of the cooler apparatus and free to slip to permit relative expansion or contraction of the tubes while minimizing leakage into the drain cooler section.

These and other objects are effected by the invention as will be apparent from the following description and claims taken in connection with the accompanying drawing, forming a part of this application, in which:

Fig. 1 is a longitudinal sectional view of a heat

2

exchanger or feedwater heater having a drain cooler section constructed in accordance with the invention;

Fig. 2 is a sectional view taken along the line II—II of Fig. 1;

Fig. 3 is an enlarged detail sectional view of the drain cooler seal structure shown in Fig. 1; and

Fig. 4 is a sectional view taken along the line IV—IV of Fig. 3.

In the drawing, there is shown a feedwater heater including a shell 10, a header 11 having an inlet compartment 12 and an outlet compartment 14, and a plurality of "hairpin" or U tubes 15, the opposite open ends of which are rolled into the usual tube sheet 16 of the header for communication with the inlet and outlet compartments thereof, respectively. Water to be heated is supplied to the inlet compartment 12, flows through the first and second passes *a* and *b* of tubes 15, and heated water is discharged from the outlet compartment 14.

A horizontal and enveloping baffle structure 23 having one end secured to the tube sheet 16 surrounds a portion of the first pass *a* of the tubes 15. An interior tube plate 25 secured to a baffle section 23a is provided adjacent the inner end of the enveloping baffle structure 23 for cooperating therewith to divide the interior of the shell

10 into feedwater heating spaces 27 and 28. The space 27 has an entryway 27a and an outlet 27b, and is adapted to serve as a drain cooler section extending for a portion of the first pass *a* of the tubes 15. The larger heating space 28 has an inlet 28a and is adapted to facilitate transfer of heat from steam into the water flowing through the tubes 15 to effect consequent condensation of the water vapor. A number of laterally disposed deflector plates 30 and 31 of

smaller diameter than that of the shell 10 are mounted in the space 28 for providing staggered flow ports for effecting flow through a tortuous flow path of the steam entering the space. Heating steam thus enters the inlet 28a adjacent the header end of the space 28, is driven to and fro as it impinges against the deflectors 30, and thence flows upwardly and downwardly around the deflectors 31, thereby being passed in heat exchanging relation over both passes of the tubes 15.

Condensate collecting at the bottom of the shell 10 is driven by steam pressure into the drain cooler space 27, through the inlet 27a, which is formed at the lower chordal edge of the tube plate 25. To provide for alternate back

and forth flow of condensate across the portions of the tubes 15 within the drain cooler space 27, lateral baffles 42 are provided therein, with staggered upper and lower chordal edges spaced at opposite sides of the space to form suitable flow port areas. Discharge flow of condensate from the drain cooler section is effected by way of the outlet 27b.

The tubes of the first pass *a* are expanded or rolled into the openings provided in the interior tube plate 25, whereby fluid-tight connections are ensured. According to the invention, as best shown in Fig. 3, an expansion joint assembly 45 is provided between the baffle structure 23 and baffle section 23a comprising outer and inner circumferential sealing plates 46 and 47 carried by and extending coaxially of the baffle structure and separated by a relatively narrow spacer 48, and spaced circumferential outer and inner circumferential sealing plates 49 and 50, which are interleaved with the sealing plates 46 and 47 and carried by the baffle section 23a. A narrow spacer 51 is interposed between the sealing plate 50 and baffle section 23a, while the sealing plates 49 and 50 are spaced by a similar spacer 52 to provide for coaxial alignment of the respective interleaved plates of the separate elements of the drain cooler section. It will be understood that, with the sealing plates of the joint assembly 45 slidably interengaged, and with the tube plate 25 secured to portions of the tubes 15 remote from the ends thereof which are rolled into the tube sheet 16, as shown in Fig. 1, any thermal expansion and contraction of the tubes will be effected without undesirable concentration of stresses in the structural portions of the heat exchanger, due to the relative slipping permitted between the interleaved sealing plates. At the same time, an effective seal is maintained by the joint assembly 45, preventing leakage of steam or condensate from the spaces of the heat exchanger to which those fluids are to be confined.

While the invention has been shown in but one form, it will be obvious to those skilled in the art that it is not so limited, but is susceptible of various changes and modifications without departing from the spirit thereof.

What is claimed is:

1. In a heat exchanger having a horizontally disposed shell and header structure forming a heating space, means for admitting steam thereto, water tubes horizontally mounted therein and providing first and second passes, baffle structure enveloping portions of said tubes in one of said passes for enclosing a drain cooler section, said baffle structure including a horizontally disposed main portion and a relatively movable interior tube plate portion having openings in which said tubes are secured intermediate the ends thereof, said interior tube plate portion having a lower recessed edge forming an entryway for admission of condensate from said heating space to said drain cooler section, and expansion joint means interposed between said main portion of the baffle structure and said interior tube plate portion, comprising a plurality of interleaved plate elements carried by the respective main and tube plate portions of said baffle structure, said plate elements being slidably engaged in sealing relation.

2. In a heat exchanger having a horizontal shell and a header structure forming a heater space, means for admitting steam thereto, water tubes horizontally mounted therein and providing first and second passes, baffle structure en-

veloping portions of said tubes in one of said passes for enclosing a drain cooler section, said baffle structure including a horizontally extending main portion and a relatively movable interior plate tube portion having openings in which said tubes are secured intermediate the ends thereof, said interior tube plate portion having a lower recessed edge forming an entryway for admitting condensate from said heater space to said drain cooler section, and expansion joint means interposed between said main portion of the baffle structure and said interior tube plate portion, said expansion joint means including a plurality of overlapped, spaced plates circumferentially mounted on said baffle structure, and a plurality of similar plates complementary to the first-named plates and circumferentially carried by said tube plate portion, said separate groups of plates being slidably interengaged to provide an expansible sealed joint.

3. In a feedwater heater, a horizontally disposed shell forming a heater space, a header connected to the shell and including an outer tube plate, said header having a lower inlet compartment for water to be heated and an upper outlet compartment for heated water, horizontally disposed tubes having ends joined to said outer tube plate and forming lower and upper passes for conducting water from said inlet compartment to said outlet compartment, horizontal and enveloping baffle structure joined to the tube plate and encompassing the tubes of said lower pass for a portion of the length thereof to constitute a drain cooler section separate from said heater space, an interior tube plate having openings for receiving said tubes and secured thereon adjacent said baffle structure, said interior tube plate having a recessed lower edge forming an entryway for admission of condensate to said drain cooler section, a condensate discharge outlet arranged thereabove, said shell having a steam admission opening formed in the end thereof adjacent said header and communicating with said heater space, and expansion joint means comprising complementary plates slidably interposed between and connecting said interior tube plate and said baffle structure in sealed relation for minimizing leakage of steam from said heater space into said drain cooler section.

4. In a feedwater heater, a horizontally disposed shell forming a heater space, a header connected to the shell and including an outer tube plate, said header having a lower inlet compartment for water to be heated and an upper outlet compartment for heated water, horizontally disposed tubes having ends joined to said outer tube plate and forming lower and upper passes for conducting water from said inlet compartment to said outlet compartment, horizontal and enveloping baffle structure joined to the tube plate and encompassing the tubes of said lower pass for a portion of the length thereof to constitute a drain cooler section separate from said heater space, an interior tube plate having openings for receiving said tubes and secured thereon adjacent said baffle structure, said drain cooler section having a condensate entryway formed by a recessed lower edge on said interior tube plate and a discharge outlet arranged thereabove, said shell having a steam admission opening formed in the end thereof adjacent said header and communicating with said heater space, and expansion joint means interposed between and connecting said interior tube plate and said baffle structure for minimizing leakage of steam from said heater space into said

drain cooler section, said expansion joint means comprising overlapping, spaced inner and outer concentrically curved plates carried by said baffle structure, and overlapping, spaced inner and outer concentrically curved plates carried by said interior tube plate and interleaved in slidable sealing engagement with the first-named plates.
